KEY LOCKING DEVICE

Oscar C. Gruender, Milwaukee, Wis., assignor to
 Nordberg Manufacturing Company, Milwaukee,
 Wis., a corporation of Wisconsin

Application November 20, 1951, Serial No. 257,358

7 Claims. (Cl. 241—285)

1

My invention relates to an improvement in gyratory crushers and has for one purpose to provide an improved locking assembly for the bowl or bowl support of the crusher.

Another purpose is to provide an adjusting and locking assembly for gyratory crushers with vertically adjustable bowls in which the adjusting members are under compression instead of tension.

Other purposes will appear from time to time in the course of the specification and claims.

I illustrate the invention more or less diagrammatically in the accompanying drawings wherein:

Figure 1 is a plan view with parts omitted;

Figure 2 is a vertical axial section on the line 2—2 of Figure 1;

Figure 3 is a partial side elevation on an enlarged scale;

Figure 4 is a section on the line 4—4 of Figure 3; and

Figure 5 is a section on the line 5—5 of Figure 3.

Like parts are indicated by like symbols throughout the specification and drawings.

Referring to the drawings, I generally indicate a circumferential main frame member, having an outwardly extending top flange 2. Connected to, or formed integrally with the circumferential main frame member 1, is an internal hub 3 within which the normally fixed central pillar 4 is secured. The pillar 4 has an upwardly extending shaft portion 5 having a generally cylindrical exterior bearing surface 6. The central hub or fixed sleeve 3 of the frame is connected to the circumferential frame member by any suitable outwardly extending spider portions 7. I illustrate also an intermediate frame portion 8, supporting a bearing ring 8a, having a generally spherical bearing surface concentric with the point X.

Mounted for rotation about the bearing 6 of the post 5 is an eccentrically apertured sleeve 9. The sleeve 9 has an inner bearing surface or element 10 surrounding and conforming to the exterior bearing surface 6 of the post 5. It is formed also with an outer cylindrical bearing surface 11. The axes of its inner and outer bearing surfaces are at a slight angle to each other, but converge and intersect at the point X of Figure 2.

12 generally indicates a gyrated head structure. The head is shown as having a generally central downwardly extending sleeve 13 surrounding and conforming generally to the bear-

2

ing surface 11. It may include an internal removable bearing sleeve 13a. It also has a generally cylindrically surfaced spherical bearing portion 14 received upon the removable bearing ring 8a on the cylindrical bearing support 8. It will be understood that the parts are so formed that when the sleeve 9 is rotated it imparts gyration to the head about the center X, the head being supported upon the circumferential bearing 8.

As means for rotating the sleeve 9 and thus gyrating the head, I illustrate any suitable drive shaft 15, carrying a pinion 16 in mesh with a gear 16a, secured to or positioned on the lower end of the eccentrically apertured sleeve 9. Any suitable pulley, or other means not herein shown, may be employed to impart rotation to the shaft 15 and thus gyration to the head. The head is shown as carrying any suitable crushing ring or member 17, opposed to the crusher bowl liner 18.

10 In order to support the bowl liner 18 and to provided a normally fixed member toward and away from which the gyrated crushing ring 17 moves, I provide the following structure. Removably secured upon the top flange 2 of the main frame member 1, I illustrate the ring 20 having a circumferential downwardly extending flange 21, which surrounds and conforms to the outer edge of the flange 2. The ring 20 is provided with an inward upwardly extending flange 22, having an inner conic face 23 and an outer generally upright face 24. 25 is a bowl support apertured to conform generally to the flange 22. It is normally held fixed in relation to the flange 22 by tension members or bolts 26, which pass through the ring 20 and the flange 2 and are surrounded by compressed coil springs 27 and which are normally effective firmly to hold the bowl support 25 in the position in which it is shown in Figure 2. However, they will yield to predetermined excess crushing stresses. It will be understood that any suitable abutment or abutments at the ends of the bolts 26 may be adjusted to maintain any desired compression on the springs 27.

45 The bowl support 25 is provided with a suitable number of outwardly extending lugs 28, apertured as at 29 to permit the passage therethrough of the bolts 26, the bolts being upwardly headed as at 30. The bowl support 25 includes a generally cylindrical upward extension 35, this extension being inwardly screw-threaded as at 36. The bowl proper 37 has a generally cylindrical outer portion 38 externally screw-threaded as at 39 in mesh with the internal screw threads of the members 35 and 36. The bowl liner 18 is

secured to the bowl 37 by any suitable locking assembly, generally indicated as including the parts 40 and 41, the details of which do not of themselves form part of the present invention but are described and claimed in my copending application 317,193, filed October 28, 1952, and are disclosed in my copending application 161,769, filed May 13, 1950 now Patent Number 2,670,142. 42 is any suitable hopper member, removably secured to the bowl 37.

The bowl member 38 is shown as having a top outwardly extending circumferential flange 50, to which is bolted the ring 51. The ring has a plurality of lugs or abutments 52 which are preferably equally spaced. Directly below each such lug 52, I illustrate a pair of generally radial ears or projections 53 between which are located adjustment shims 54 and vertical struts 55, which engage the circumferential top flange or abutment 25a of the bowl support 25. On top of each set of shims 54 rests the grooved or recessed wedge block 56, which is tapered to accommodate the tapered key 57. A guard plate 58 may retain the wedges while the keys 57 are driven home. The shims thus employed and the vertical struts are under compression, whereas in prior art structures of relevant type tensioned adjustment screws are employed.

Referring to Figure 5, the guard plate 58 is slidably positioned within the space formed by the lugs 53 and angle members 59, which may be welded to the lugs. The guard plate 58 is provided with a flange 60 and stop members 61, which may engage the upper ends of the angle members 59, as illustrated in Figures 3 and 4.

It will be realized that whereas I have described and shown a practical and operative device, nevertheless many changes may be made in size, shape, number and disposition of parts. I therefore wish my description and drawings to be taken as in a broad sense illustrative or diagrammatic, rather than as limiting me to my specific showing herein.

The use and operation of my invention are as follows:

I illustrate a crushing or grinding structure in which the bowl 37, 38 and its supporting structure 35 are normally held in the position in which they are shown in Figure 2. Since uncrushable material, such as steel, dipper teeth or other particles of metal, may pass through the crushing zone and since material under some circumstances may pack, in the crushing zone, into an uncrushable mass, I employ yielding means which include the bolts 26, which may be surrounded by springs 27, or which, if desired, may be used in connection with pneumatic or hydraulic crusher cylinders. The bowl 37, 38 is adjustable on or in the bowl support 35. In order to hold it in adjusted position and to reduce the shock to the threads, I provide the above-described adjusting shims 54 beneath the wedge blocks 56, which receive the tapered keys 57. The tapered keys 57 are driven between the wedge blocks 56 and the lugs or abutments 52. The vertical struts 55 and the shims are under compression and no tensioned members are employed in connection with the adjustment of the bowl and the locking of the bowl in adjusted position.

I claim:

1. In a supporting and locking assembly for

an adjustable crusher bowl adapted for use with a gyrated crusher head, a bowl supporting ring, a bowl structure mounted on and adjustable in relation to said ring, and a locking assembly interposed between said ring and said bowl structure, including an abutment on said ring, an opposed abutment on said bowl structure and a tapered key wedged between said abutments and adapted to maintain said locking assembly under compression between said ring and bowl structure.

2. The structure of claim 1, characterized by and including a plurality of said locking assemblies circumferentially spaced about the exterior of the bowl structure.

3. The structure of claim 1, characterized in that said locking assembly includes a plurality of shims interposed between and under compression between said key and one of said abutments.

4. The structure of claim 1, characterized in that said locking assembly includes a strut and a wedge block interposed between said key and one of said abutments and positioning means for guiding the key and for guiding the strut.

5. The structure of claim 1, characterized in that said locking assembly includes a guide formed on the exterior of the bowl structure, and a strut within said guide, said key being formed and adapted to maintain said strut in compression between the ring and the bowl structure.

6. The structure of claim 1, characterized in that said locking assembly includes a plurality of shims positioned between said key and one of said abutments, and means for preventing unintended movement of said shims, said key being adapted to apply compression to said shims, whereby the locking assembly is put in compression between the ring and the bowl structure.

7. In a supporting and locking assembly for an adjustable crusher bowl adapted for use with a gyrated crusher head, a bowl supporting ring member, a bowl structure member threadedly mounted on and adjustable in relation to said ring member, and a locking assembly interposed between said ring member and said bowl member, said locking assembly including abutment means on each of said members, guide means on one of said members, a strut positioned within said guide means and abutting against one of said abutment means, a wedge block positioned within said guide means, a tapered key forced between said wedge block and the abutment means on the other member, said wedge block having a recessed edge, said key being seated in said recessed edge, and a plurality of shims compressed between said wedge block and an edge of said strut within said guide means and compressed upon the entrance of said key between said block and said wedge abutting means.
